UNITED STATES PATENT OFFICE.

WILLIAM RANSWEILER, OF AKRON, OHIO.

BABY-JUMPER.

SPECIFICATION forming part of Letters Patent No. 375,096, dated December 20, 1887.

Application filed April 8, 1887. Serial No. 234,140. (No model.)

To all whom it may concern:

Be it known that I, WILLIAM RANSWEILER, a citizen of the United States, residing at Akron, in the county of Summit and State of Ohio, have invented certain new and useful Improvements in Baby-Jumpers; and I do hereby declare the following to be a full, clear, and exact description of the invention, such as will enable others skilled in the art to which it applies to make and use the same.

The object of my invention is to provide a cheap, strong, and durable baby-jumper which can be easily adjusted to suit a reclining or sitting position, so that the occupant can be made to sit upright or to lie down full length; and a further object is to so construct the device that it can be easily knocked down and packed in a very small space for shipping purposes.

To this end my invention consists in the peculiar construction and combinations of parts more fully described hereinafter, and pointed out in the claims.

Referring to the accompanying drawings, Figure 1 represents a perspective view of my complete device; Fig. 2, a view showing the device knocked down and ready for shipment, and Fig. 3 a detail view of the back and adjusting-clamps.

The letter *a* represents the seat of the chair, having upon either side thereof a pair of longitudinal side bars, *b*, connected together by lateral girders *c*, upon which the seat *a* rests. The arm-rests *d* are supported upon transverse spokes *e*, the opposite ends of which are removably fitted within the sockets *f*, and the sides thus formed are rigidly bound together by stay-rods *g*, which pass transversely through the front and rear ends of the arm-rests and side bars. The upper ends of these stay-rods are provided with eyes *h*, adapted to receive the supporting-ropes *i*.

The adjustable back consists of a board or suitable bearing-piece, *j*, held between the free ends of the pivoted arms *K* by means of the screws *l* and flanges *m*. In order to hold the back at any desired angle, I provide each arm with a pair of clamping-disks, *N N'*. The disk *N* is made integral with the pivoted end of the arms *K* and surrounds the head of the pivot *O*, which head is countersunk in the outer face of the disk *N*, and the opposite engaging-face

of this disk is provided with an embossment, *p*, which fits within a corresponding depression in the opposite engaging-face of the stationary disk *N'*, and this disk is rigidly secured to one of the rear spokes, *e*, by means of a transverse concavity, *q*, within which the spoke fits, and is thereby prevented from turning with the opposite disk, *N*, during the adjusting operation. The pivot *O* passes transversely through the center of both the disks *N N'* and spoke *e*, the end which projects beyond the spoke being provided with a thumb-nut, *e'*, by means of which the disks are clamped and unclamped. A piece of flexible material, *r*, is stretched across the back between the back-piece *j* and seat *a* to form a soft support for the lower part of the child's back.

s is a pivoted foot-rest, rigidly secured to a rock-shaft, *t*, journaled in sockets or bearings *t'* in the ends of the side bars, *b*, and it is held in raised adjustment by means of cords *U*, fastened to the eyes *h* of the forward stay-rods, *g*, and the free end of the foot-rest. Besides supporting the rest, these cords also assist in keeping the child from falling out, and a hinged foot-board, *V*, which projects upward from the free end of the foot-rest, still further serves to keep the child within the jumper.

The suspending-ropes *i* each consists of a single continuous piece, each serving to support one side of the chair. The manner in which I prefer to arrange these ropes so that their length may be varied as occasion demands may be described as follows: One end of the rope is first made fast to the ring *W*. The rope then extends down through the eye *h* of the stay-rod *g*, thence upward through the same ring, around which it is given one wrap, and on through an eye in one end of the swivel-arm *y*, to which it is fastened by a slip-noose. From this point it passes down through another ring, *W'*, and is given one wrap around this ring like the other, and it then passes on down through the eye of the stay-bolt and up back to the ring, to which it is fastened. The arm *y* is swiveled to the lower end of the coil-spring *Z* by the swivel *y'*, by means of which the ropes and spring are prevented from twisting. The upper end of the spring *Z* is provided with a loop, by means of which it is hung upon any suitable pendant.

The construction of my device having been

set forth, I will now proceed to describe its operation. When it is desired to have the child kept in a sitting posture, the device is placed in the adjustment shown in Fig. 1, and in order 5 to adjust the chair so that the child can lie down all that is necessary is to first loosen the thumb-nuts e' and the back can be turned down to the position shown in dotted lines. The foot-rest is next turned up to an elevated position 10 and the hooks u' , upon the ends of the cords u , are hooked through the eyes h^2 in the free end of the foot-board, and the same is held up to support the feet of the child. In order 15 to raise or lower the chair it is only necessary to slide the rings W W' up and down, and they will remain in any position in which they are placed, and will be unaffected by the weight thrown upon the ropes. The operation of knocking the chair down 20 preparatory to shipping is performed by simply removing the stay-rods, and, as the arm-rests and spokes are only loosely joined together, they can be quickly taken to pieces. The back can be turned down upon the top of the seat, 25 the foot-board folded down, and the whole device compactly placed in a small space, as shown in Fig. 2, so that the cost of shipment will be greatly reduced.

I do not herein broadly claim a combined 30 swing consisting of a stationary seat, swinging back, sliding board, supporting-cords, swivel, and spring; but

What I do claim as new, and desire to secure by Letters Patent, is—

1. In a baby-jumper, a back provided with 35 pivoted arms having disks cast integral therewith and surrounding the pivot, said disks being provided with an embossment, in combination with a stationary disk provided with an engaging-face having a depression upon 40 one side within which said embossment is adapted to fit, and a transverse concavity upon its opposite side adapted to partially embrace a rod or spoke, and a pivot provided with a threaded end and nut, all combined and 45 adapted to operate as described.

2. The combination of the stationary seat, the lateral girders supporting said seat and connecting the side bars, the arm-rests, the spokes connecting said side bars and arm-rests, and having their ends loosely fitted in their sockets, the stay-rods adapted to removably hold the arm-rests and side bars in position, the hinged foot-rest, the adjustable back pivoted to the side frames of the seat, 50 the pivots being surrounded by clamps, whereby the back is held at the desired angle, and the adjustable supporting-ropes, all arranged and adapted to operate substantially 55 as described.

In testimony whereof I affix my signature in presence of two witnesses.

WILLIAM RANSWEILER.
